[57] **CLAIM**

The ornamental design for a pedestal housing for a septic pump control panel, as shown and described.

DESCRIPTION

FIG. 1 is a front elevational view of a first embodiment of an ornamental design for pedestal housing for a septic tank pump control panel showing my new design;

FIG. 2 is a right side elevational view thereof;

FIG. 3 is a rear elevational view thereof;

FIG. 4 is a left side elevational view thereof;

FIG. 5 is a top plan view thereof and;

FIG. 6 is a bottom plan view thereof;

FIG. 7 is a front perspective view of the ornamental design for pedestal housing for a septic pump control panel; and,

FIG. 8 is a rear elevational view of a second embodiment of ornamental design for pedestal housing for a septic pump control panel showing my new design, and other FIGS. 1, 2, 4, 5, 6, 7, and 8, are the same as for the first embodiment.
